UNITED STATES PATENT OFFICE

102,025

DESIGN FOR A DICE BOX

Milton M. Coles, Chicago, Ill.

Application February 7, 1936, Serial No. 61,018

Term of patent 3½ years

To all whom it may concern:

Be it known that I, Milton M. Coles, a citizen of the United States, residing at Chicago, in the county of Cook and State of Illinois, have invented a new, original, and ornamental Design for a Dice Box, of which the following is a specification, reference being had to the accompanying drawing, forming part thereof.

The figure is a perspective view of a dice box showing my new design.

I claim:

The ornamental design for a dice box, as shown.

MILTON M. COLES.
